(57) **CLAIM**

The ornamental design for a cutlery drawer organizer, as shown and described.

DESCRIPTION

FIG. 1 is a perspective view of a cutlery drawer organizer, showing my new design;

FIG. 2 is a top plan view thereof;

FIG. 3 is a bottom plan view thereof;

FIG. 4 is a side view thereof;

FIG. 5 is an opposite side view thereof;

FIG. 6 is a front view thereof;

FIG. 7 is a rear view thereof;

FIG. 8 is a bottom perspective view thereof;

FIG. 9 is a bottom perspective view thereof, shown in a closed condition; and,

FIG. 10 is a top perspective view thereof, shown in a closed condition.

The broken lines in the figures illustrate the portions of the cutlery drawer organizer and form no part of the claimed design.
